UNITED STATES PATENT OFFICE.

LOUIS SCHIEK AND WILLIAM SCHIEK, OF CHICAGO, ILLINOIS.

BUCKET.

1,328,458.

Specification of Letters Patent.

Patented Jan. 20, 1920.

Application filed August 10, 1917. Serial No. 185,623.

To all whom it may concern:

Be it known that we, LOUIS SCHIEK and WILLIAM SCHIEK, citizens of the United States, residing at Chicago, in the county 5 of Cook and State of Illinois, have invented new and useful Improvements in Buckets, of which the following is a specification.

This invention relates to buckets and more particularly to that type of metal bucket 10 which is especially serviceable for scrubbing purposes.

The primary object of the invention is to provide a bucket of this type in which the bottom is so constructed that a base normally forming a part of the bucket may be quickly disconnected from the bucket bottom when the occasion requires and when connected therewith will enable the bucket to be slid easily and noiselessly, from point 20 to point, over a supporting surface without injury to the bucket bottom.

Another object of the invention is to provide a bucket in which the bucket bottom has permanently connected therewith a 25 band, which not only enables the base to be connected with the bucket bottom but when the bucket is disconnected from the base spaces the bucket bottom from a support upon which the bucket may be placed, thus 30 serving as a protecting flange for the bottom of the bucket.

With these and other objects in view the invention resides in the novel combination and arrangement of parts, which will be 35 hereinafter described and particularly pointed out in the claims.

The preferred embodiment of the invention has been illustrated in the accompanying drawings, although no restriction is necessarily made to the precise details of construction therein shown, as changes, alterations, and modifications, within the scope of the claims may be resorted to when desired.

In the drawings:

45 Figure 1 is a view in side elevation of a bucket constructed in accordance with the invention and showing the same mounted upon the bucket base.

50 Fig. 2 is a bottom plan view of the bucket, the latch rods and actuating mechanism associated therewith being shown in extended position in full lines, and in retracted position in dotted lines.

55 Fig. 3 is a vertical transverse section through the bucket bottom and base.

Fig. 4 is a top plan view of the base removed from the bucket bottom.

Like characters of reference denote corresponding parts throughout the several views in the drawings.

Referring now to the drawings in detail, the letter A designates a metal bucket of the type commonly used by char-women, and the like, for scrubbing purposes, said bucket having permanently connected with the bottom thereof a band 6 extending below the bucket bottom and by means of which the bucket is supported upon a base 7.

The band 6 which is formed from any suitable material is offset adjacent one edge 70 to form an annular and flanged shoulder 8 forming a seat upon which rests the bead 9 at the bottom of the bucket and with which the band 6 is connected in any suitable manner, such as by solder, or the like. The 75 band 6 is flared outwardly below the flanged shoulder 8 and terminates in a rolled rim 10 for engagement with latch rods hereinafter described.

The base 7 includes a band 11 having a 80 reduced portion 12 to extend within the band 6 and forming an annular shoulder 13 upon which the rolled rim 10 of the band 6 is adapted to rest, said band having connected therewith the outer ends of the spokes 85 14, the inner ends of which are connected with a centrally arranged hub 15, said band having formed thereon lugs 16 arranged between the spokes 14 and having adjustably mounted therein the shanks of caster-wheels 90 17 to permit the base and bucket when mounted thereon to be slid from point to point over a supporting surface.

Underlying the spokes 14 are latch rods 18, the outer ends of which pass through 95 keeper openings 19 in the reduced portion of the band 11 and extend beyond the same to normally engage the rolled rim 10 of the band 6, while the inner ends of the rods are mounted to turn in openings 20 in the 100 corners of a latch rod actuating plate 21 mounted to turn on the shank 22 of a screw 23 passing through the hub 15 and retained therein by a nut 24, arranged within a recess 25 in the hub 15.

A coiled contractile spring 26 having connection with the band 11 and an ear 27 on the latch rod actuating plate 21 normally serves to hold the locking ends of the latch rods extended beyond the band 11 and in po- 110

sition to engage the rim 10 on the band 6, from which position the outer ends of the latch rods may be withdrawn within the keeper openings 19 in the rim through the 5 operation of the latch rod actuating plate 21 by means of operating wings 28 thereon.

When the base 7 has been connected with the bucket A as shown in Fig. 1 in the drawing, to serve as a support for the bucket 10 and as a protector for the bottom thereof, it will be seen that the bucket may be slid from point to point or turned on a supporting surface as the occasion requires with very little effort on the part of the operator 15 and when it is desired to disconnect the base 7 from the bucket, the latch rods may be moved to a retracted position to disengage the same from the rim of the band 6, by operation of the plate 21 against the influence 20 of the spring 26.

When the bucket has been disconnected from the base 7, the band 6 serves to space the bucket bottom from a support upon which the bucket is placed, thus protecting 25 the bottom of the bucket from injury.

When it is desired to connect the base 7 with the bucket, the plate 21 is operated against the influence of the spring 26 to retract the locking ends of the latch rods 30 within the keeper openings in the band 11, after which the reduced portion of the base is arranged within the band 6 and the spring 26 permitted to move the latch rods to active position.

35 From the foregoing description, taken in connection with the accompanying drawing, it is at once apparent that a bucket has been provided which has a base removably connected therewith and not only serving

to permit the bucket to be slid easily and 40 noiselessly over a supporting surface but also preventing the bucket bottom from becoming injured or damaged while in use.

Having thus described the invention, what is claimed as new, is:

1. A bucket having a band secured to and extending below the bottom thereof, a bead on said band, a wheeled base extending within said band and engaging said bead, and spring controlled latch rods having 50 locking ends extending beyond said base and engaging said bead.

2. A bucket having a flanged and shouldered bead secured to the bottom thereof and extending below the same, a bead on 55 said band, a wheeled base having a rim extending within said band and engaging said bead, spring controlled latch rods mounted to slide in said rim and having locking ends normally engaging said bead, 60 and means for disengaging the ends of said latch rods from said bead.

3. A bucket having a band fixed to the bottom thereof, a bead on said band, a base having a shouldered rim extending within 65 said band and engaging said bead, caster-wheels adjustably connected with said rim, a latch rod actuating plate mounted to turn on said base, latch rods operatively connected with said plate and having ends 70 extending beyond said rim to engage said bead, and means connected with said plate and rim for normally holding said rods in engagement with said bead.

In testimony whereof we affix our signatures.

LOUIS SCHIEK.
WILLIAM SCHIEK.
